UNITED STATES PATENT OFFICE

BERNARD R. SCHNEIDER, OF LYNDHURST, AND KARL KAISER, OF RIDGEFIELD, NEW JERSEY, ASSIGNEES, BY MESNE ASSIGNMENTS, TO S. KARPEN & BROS., OF CHICAGO, ILLINOIS, A CORPORATION OF ILLINOIS

SPRING TURNING MECHANISM

Application filed March 16, 1931. Serial No. 523,088.

The invention relates to novel and improved mechanism for positioning springs in the pockets of a continuous fabric strip.

Fabric strips with helical or other coil springs inserted in proper position in their pockets are utilized in upholstery of various classes and especially mattresses and the like. By preferred methods or mechanism the springs are inserted in such position that their axes are perpendicular to the normal plane of the strip; that axial direction represents the shortest dimension of the pocket when distended by the spring and it is desirable to turn the springs so that their axes are parallel in a transverse direction to the normal plane of the strip; this represents the longest dimension of the pocket, so that after proper turning, the spring is positioned in the desired manner lengthwise of this longest pocket dimension.

The present mechanism receives and advances the strip and successively positions the springs (and corresponding pocket portions of the strip) for the turning operation, and while so positioned effects turning to the proper position, as above referred to, rapidly, efficiently and accurately by novel means for fabric manipulating or pinching, and pushing action exerted upon the spring ends at opposite sides thereof, whereby the spring is properly and quickly turned without injury to the fabric; the strip is then advanced to position the next spring and pocket for the turning action, and so on.

The characteristics and advantages of the invention are further sufficiently explained in connection with the following detailed description of the accompanying drawings, which show a representative embodiment. After considering this example, skilled persons will understand that many variations may be made without departing from the principles disclosed, and we contemplate the employment of any structures that are properly within the scope of the appended claims.

Fig. 1 is a side elevation of mechanism embodying the invention in one form;

Fig. 2 is a front elevation (looking toward the right of Fig. 1);

Fig. 3 is a detail in the plane of, or from

the same viewpoint as Fig. 2, showing especially the vibratory spring manipulating fingers and one stage of the turning operation;

Fig. 4 is an elevation at the right of Fig. 3; and

Figs. 5, 6 and 7 are plan views of the strip and spring at the turning station showing successive stages of the turning action.

Any suitable mechanism may be employed for receiving the fabric for registry relative to the spring turning elements, and accordingly the illustrated mechanism serves as an example of one embodiment of such mechanism.

Referring first to Figs. 1 and 2, a standard or frame upright 1 supports a bearing sleeve 2 in which a turret shaft 3 is revolvably mounted. At its inward end this shaft carries a plate 4 in which near its periphery are mounted axially extending rods 5, circularly arranged and spaced in agreement with the spacing of the transverse, sewed strip portions 6, Figs. 4, 5, etc., between the pockets 7 of the continuous fabric strip 8. This strip is folded at one edge and has the other longitudinal edge connected by stitching 9 to form the pockets in each of which a spring 10 has been placed with its axis perpendicular to the broad plane of the strip, as sufficiently shown in Fig. 2. The turret including plate 4 and rods 5, acts as means for feeding or advancing and positioning the spring containing strip at the turning position or station wherein a strip portion or pocket and spring is shown, in Figs. 1 and 4.

The turret is rotated intermittently to advance the strip by ratchet mechanism including a ratchet wheel 15 fixed on the outward end of shaft 3 and having teeth 16 engaged by a pawl 16a pivotally connected to a rock lever 17 which is mounted to oscillate on shaft 3 or about the shaft bearing 2. As shown, the spacing of the ratchet teeth 16 is such that two of them correspond to a pocket space of the fabric strip and the pawl is therefore moved to advance the ratchet wheel and turret two tooth spaces in each action; but evidently the spacing of the ratchet teeth or of the notches engaged by the pawl may be changed if desired, so that each tooth or

100

5 pawl notch corresponds to one strip-pocket length. The rock lever 17 is oscillated at proper times by a link 18 connected to a lever 19 which has a cam roll 20 engaging the periphery of a cam 21, which is fixed on a shaft 22 mounted in bearings in frame uprights or standards 23, 24. This is one of the main drive shafts of the machine. The lever is 10 fulcrumed on a shaft or bar 25 mounted in lower portions of the standards 23, 24 and is urged in the return direction by a spring 26. The spring thus acts to retract pawl 16, and the cam advances the pawl to rotate the turret in the feeding action at the proper time, 15 as will appear.

20 Suitable means are provided for effecting proper final positioning of each spring relative to the fabric. As explained hereinabove, it is advantageous to locate each spring in a 25 position relative to the fabric other than in the final position of each spring. In the manufacture of upholstery cushioning, the fabric is preferably pre-formed with partition stitchings, weavings, etc., such partition connections preferably securing the upper and lower layers of the fabric directly to one another, the mouths of the pre-formed pockets being disposed at one longitudinal side only of the fabric, the greatest dimension of 30 the pocket being disposed in the direction in which each spring is inserted in its pocket, and after insertion of each spring, the fabric is sewed to close the mouths at such longitudinal edge.

35 In the embodiment of this feature of our invention, as illustrated in the drawings, we provide means for positively registering each spring prior to the application of the spring turning elements to the spring. One such 40 embodiment of positive registry is in the form of a turret, as illustrated and described hereinabove. For this purpose the turret plate 4 is in its periphery notches 30 spaced in accordance with the fabric pocket length 45 (or spacing between rods 5). A locking or registering member 31 has its end 32 shaped to fit the notches which are usually of tapered form as shown, and is mounted to reciprocate in guides in a supporting arm 33, extending from standard 1. The locking member is urged to engage in the successive notches by a spring 34 and is retracted to permit the feeding action by a lever 35 fulcrumed on the fixed shaft or bar 25 above mentioned and having a cam roll 36 engaging the periphery of a cam 37 on shaft 22.

60 To properly hold the strip and pocket in turning position, the strip portions 6 intermediate the pocket are engaged by the ends 65 of spring-pressed plungers 40, carried by short arms or lugs 41 on rods 42 extending from the upper arms of crank-levers 43, which are fulcrumed at 44 at opposite sides (as viewed in front elevation, Fig. 1) of an upward extension 45 of standard 1, on arms

46 extending laterally therefrom. This extension or standard portion has guides 47, 48 for a vertically movable slide 49, which has a lug with a horizontal face 50 engaging rolls 51 carried by the crank-levers 43. The slide is moved to operate the crank levers, to retract and advance the retaining plungers at the proper times, by a lever including arms 53 and 54, fulcrumed at 55 on a frame piece connected to arm 33. Lever arm 53 has its end located under a roll 56 on the lower end of slide 49, and arm 54 has a cam roll 57 engaging the periphery of a cam 58 fixed on shaft 22, and designed to advance or permit advance of the spring plungers 40 after a strip pocket has come to rest in turning position, this advance being effected by gravity due to the weight of levers 43, or, if desired, by springs applied to them (not here shown). After the turning operation and before the turret moves to advance the strip, the cam raises the spring plungers to positions clear of the strip and pockets.

50 The turning mechanism proper, constituting a principal feature of the invention, comprises pairs of fingers located respectively above and below the spring and pocket and at the turning station, with means for rapidly vibrating, or moving the fingers convergently and divergently and at the same time advancing the two pairs of fingers to engage the fabric constituting the pocket and to act through the fabric upon the spring, as more fully described below. The upper and lower turning mechanisms 60 are substantially identical. Each includes a body or slide 61 having spaced bearing sleeves 62 mounted to slide on a shaft 63. The upper shaft is located above the turret, that is, above the strip-supporting rods 5 while the lower shaft extends within the turret, that is, to a position below the two uppermost rods (see Figs. 1 and 2).

55 The shafts 63 are mounted to rotate in bearings 64 in an upright frame structure 65. A cam-sleeve or eccentric-sleeve 66 is mounted slidably on each shaft 63 between the adjacent ends of the bearings 62 of the corresponding slide 61 and connected by a key or spline engaging in a spline channel 67 of the shaft to turn therewith. This sleeve has two oppositely arranged or acting cams or eccentrics 68 acting on cam rolls 69 of arms or levers 70 located at opposite sides of the shaft and fulcrumed at 71 on bearing pins in lugs 72, on the slide. The arms 70 thus extend respectively downward and upward from the upper and lower turning structures, and have at their ends adjacent the fabric strip, turning fingers 73 which are preferably, as best shown in cross-section in (Figs. 5 to 7), of generally triangular form, providing angularly arranged active serrated faces 74, to cooperate with the strip fabric and spring in either direction of movement, as will appear. The arms 70 and fingers 73 are urged to move con-

vergently by springs 75 tensioned between the arms.

Each slide is held and guided in proper position as it reciprocates on its shaft 63, by 5 a gib or key 76 engaging in a channel 77 carried by an arm 78 extending from the frame structure 65.

The slides are reciprocated at the proper times, simultaneously in opposite directions, 10 by oppositely-directed levers 80, 81, fixed on a rock shaft 82 mounted in a bearing in frame structure 65. The ends of these levers are connected to the respective slides 61 by links 83, and one of the levers or lever links is connected as by a link 84 to a main slide-operating lever 85, which is fulcrumed at 86 at the base of the frame structure 65 and has a cam roll 87 engaging in a cam track 88 of a cam body 89 secured on a shaft 90, which is 20 arranged at a right angle to shaft 22 previously mentioned and connected to it by bevel gears 91 of such diameters that shaft 90 rotates at one-half the speed of shaft 22. Either of these shafts may be considered the 25 initial or primary driving shaft of the machine, or of all of its mechanism except the means for vibrating or oscillating the turning fingers.

Independent drive for the finger oscillating function is most desirably provided, since 30 these fingers are preferably vibrated or oscillated at high speed. Such independent driving means is represented by sprockets 95 on shafts 63 connected by a chain 96, and 35 a pulley 97 on one of the shafts, which is driven by a belt 98 from the pulley of an electric motor, or in any other convenient way, to rotate shafts 63 at the desired high speeds.

The fabric strip coming from the spring 40 inserting mechanism (which is toward the left side of the turret, as viewed in Fig. 1), with the springs located in the pockets with their axes perpendicular to the normal plane 45 of the strip, that is, in radial relation to the turret axis up to the point of turning, and expanded to the extent permitted by distension of the pocket material in the stated direction, is engaged with the turret rods 5 in a manner easily understood in Figs. 1 and 2; 50 that is, with each inward portion of a pocket located between two of the rods and with the intermediate flat portions of the strip lying upon the rods so that the turret with its rods acts practically as a sprocket to positively advance the strip and position one 55 pocket and spring for turning, in a manner sufficiently explained above. While the spring and pocket are moving to such position the heads or slides 61 carrying the turning 60 fingers 73 are retracted laterally, one of the heads with its fingers being located to one side of the strip, as viewed in Fig. 2, and the other head and fingers being located near the other side, these positions in each 65 successive turning action being relatively

reversed, as will appear. The fingers on each pair, that is, those carried by each slide 61, are continuously vibrated or moved rapidly toward and away from each other by rotation of shafts 63. Cam 88 now acts to move the two slides convergently with relation to the spring and strip center, bringing the fingers into engagement with the fabric pocket material, which is pressed against rounded contours of the upper and lower portions of 75 the spring respectively, and moved or agitated in relation to the spring as the slides advance, and the fingers act on the spring to turn it in the manner clearly indicated in Fig. 3, in which the spring has been partly 80 turned, (successive positions during turning being shown in Figs. 5 and 6) and by the progressive movement of the slides and fingers the spring is finally turned through an angle of 90° or to the final position, as shown 85 in Fig. 7, in which its axis is parallel to the widthwise plane of the strip. The spring now occupies the longest dimension of the pocket and expands to the desired degree as 90 controlled by the pocket length.

The two sets of fingers which, in the first part of the turning operation, move convergently, pass each other at about the mid-point of the turning action and then move divergently (with respect to the strip center) and finally when turning is completed each pair is located at the side of the strip opposite to its first position.

The holding plungers 40 are now retracted, the locking member 31 is retracted to free 100 the turret, and the ratchet mechanism acts to turn the turret a distance equal to one pocket length (lengthwise of the strip); the turret is again locked, the holding plungers are advanced to grip the fabric upon the two 105 uppermost rods 5, and the turning slides are then moved in the opposite direction to that first mentioned for another turning action; and those actions are repeated indefinitely.

It will now be understood that shaft 90 is 110 connected to shaft 22 to turn at one-half the speed of the latter so that cam 89 will make only one-half turn during a complete turn of shaft 22, to traverse the turning slides in only one direction in each machine cycle or turning 115 action.

The rapid vibration of the turning fingers does not exert a beating action upon the springs, but rather a vibratory pushing action exerted continuously and smoothly in 120 one direction (with respect to each pair of fingers) and with accompanying alternating pinching and releasing actions on the fabric whereby the spring is caused to turn freely within the pocket and is practically positively rotated by the oppositely exerted pressure of the fingers at the top and bottom of the spring. Turning is also expedited or facilitated after the action is approximately one-half completed (or when in 125

the position shown in Fig. 6), by the natural expansive tendency of the spring, which causes it to seek the position of greatest expansion, namely, lengthwise of the pocket 5 in a transverse direction of the strip, as shown in Fig. 7.

From the above, it is apparent that the invention is applicable of embodiment in various mechanical forms providing for the 10 positioning of the fabric at successive stages and the turning of the springs within the fabric pockets successively at the respective stages by the disclosed instrumentalities for imparting a succession of vibratory spring 15 turning movements by engagement with the fabric.

The periodicity of the vibratory movement may be in correspondence to the natural period of vibration of the springs, subject to 20 the damping action of the enclosing fabric.

Whereas the invention has been set forth by reference to specific forms of the invention, it will be understood that many changes and modifications may be made without departing from the spirit of the invention. 25

We claim:—

1. A spring turning machine comprising means for positioning a fabric strip formed with pockets and springs contained in the 20 pockets, and turning mechanism including oppositely pairs of fingers arranged to move in continuous direction to cooperate with opposite sides of the spring at opposite ends thereof and turn it within the pocket, and 25 means for vibratory moving the fingers during the turning action.

2. A spring turning machine comprising means for positioning a fabric strip formed with pockets and springs contained in the 40 pockets, turning mechanism including oppositely moving supports, pairs of fingers on the supports arranged to move in continuous direction to cooperate with opposite sides of the spring at opposite ends thereof and turn 45 it within the pocket, and means for vibratory moving the fingers during the turning action.

3. A spring turning machine comprising means for positioning a fabric strip formed 50 with pockets and springs contained in the pockets, and turning mechanism including supports arranged for opposite movement toward the pocket and spring, a pair of fingers on each support, and means for rapidly convergently and divergently moving the fingers of each pair.

4. A spring turning machine comprising means for positioning a fabric strip formed with pockets and springs contained in the 60 pockets, turning mechanism including supports arranged for opposite movement toward and past the pocket spring, a pair of fingers on each support, means for rapidly convergently and divergently moving the fingers of each pair.

5. A spring turning machine comprising means for positioning a fabric strip formed with pockets and springs contained in the pockets, turning mechanism including supports arranged for opposite movement toward the pocket and spring, a pair of fingers on each support, means for rapidly convergently and divergently moving the fingers of each pair, and means for moving the supports simultaneously in opposite directions 70 in one turning action and substantially simultaneously in respectively reversed directions 75 in the next turning action.

6. A spring turning machine comprising means for positioning a fabric strip formed with pockets and springs contained in the pockets, turning mechanism including supports arranged for opposite movement toward and past the pocket spring, a pair of fingers at each support, means for rapidly convergently and divergently moving the fingers of each pair, and means for moving the supports simultaneously in opposite directions 80 in one turning action and simultaneously 85 in respectively reversed directions in the next turning action.

7. A spring turning machine comprising a strip advancing instrumentality having members to engage and support transverse strip portions intermediate pockets thereof 90 containing springs, means for moving said instrumentality to successively position the springs for turning, means for clamping the intermediate strip portions on the supports while turning, turning mechanism acting on 100 opposite sides of opposite ends of the spring through the pocket material, said turning mechanism comprising pairs of relatively movable fingers and means for rapidly moving the fingers of each pair convergently and 105 divergently during advance in contact with the spring.

8. Spring turning mechanism comprising a turret having strip supporting rods, means for rotating the turret to position the springs 110 for turning, and turning mechanism comprising oppositely movable slides and vibratory turning fingers thereon.

9. Spring turning mechanism comprising a turret having strip supporting rods, means for rotating the turret to position the springs for turning, turning mechanism comprising oppositely movable slides and vibratory turning fingers thereon, rotary shafts supporting the slides, and cams on the shafts for actuating the fingers. 115

10. Spring turning mechanism comprising a turret having strip supporting rods, means for rotating the turret to position the springs for turning, turning mechanism comprising oppositely movable slides and vibratory turning fingers thereon, rotary shafts supporting the slides, cams on the shafts for actuating the fingers, and means for rotating the shafts at high speed. 125

11. Spring turning mechanism comprising a turret having strip supporting rods, means for rotating the turret to position the springs for turning, turning mechanism comprising 5 oppositely movable slides and vibratory turning fingers thereon, rotary shafts supporting the slides, cams on the shafts for actuating the fingers, and means independently of said turret rotated means for rotating the 10 shafts at high speed.

12. A turning instrumentality for purposes described, comprising a slide, a driving shaft, arms connected to the slide, a 15 spring urging the arms convergently, cams

on the shaft for moving the arms divergently, and turning fingers at free ends of the arms.

13. A turning instrumentality for purposes described, comprising a slide, a driving shaft, arms connected to the slide, a 70 spring urging the arms convergently, cams on the shaft for moving the arms divergently, and turning fingers at free ends of the arms, the fingers having angularly arranged turning faces. 75

In testimony whereof we have signed this specification this 13th day of March, 1931.
